Philip Parnsworth

UNITED STATES PATENT OFFICE.

JOHN A. PROCTOR, OF LEXINGTON, MASSACHUSETTS, ASSIGNOR TO WIRELESS SPECIALTY APPARATUS COMPANY, OF BOSTON, MASSACHUSETTS, A CORPORATION OF NEW YORK.

RADIO RECEIVING APPARATUS.

Application filed July 6, 1920, Serial No. 394,063.

To all whom it may concern:

Be it known that I, JOHN A. PROCTOR, a citizen of the United States of America, and a resident of Lexington, State of Massachusetts, have invented certain new and useful Improvements in Radio Receiving Apparatus, the principles of which are set forth in the following specification and accompanying drawings, which disclose the form of the invention which I now consider to be the best of the various forms in which the principles of the invention may be embodied.

This invention relates to receiving systems for wireless signals and particularly to such systems in which a closed or coil aerial is associated with an open aerial or antenna, in the manner disclosed in Fig. 3 of United States Patent No. 876,996 to G. W. Pickard. In such systems, there is a combination of loop action and open antenna action, and the combined effects of the currents in the loop and in the open antenna, in proper phase relation, are brought to bear on a receiving instrument. Such systems have great value in their capacity to eliminate both the effect of static and other atmospheric disturbances and the effect of interference from other stations than the one from which it is desired to receive signals.

The object of this invention is to modify or improve upon such systems in a manner to improve the directional effects thereof, and thereby to improve the action in eliminating interference and static.

In systems comprising a combination of open and closed aerials, it is very difficult to arrange the aerials electrically symmetrical relative to each other or one part of the loop aerial electrically symmetrically relatively to another part to avoid undesirable currents, such as "antenna effect" in the loop, due to this unbalanced or unsymmetrical relation. This unbalancing is especially noticeable where the closed aerial constitutes a part of the open aerial and where the part of the open aerial to ground or counterpoise is connected to the loop electrically unsymmetrically. The undesirable currents above referred to which are out of phase with the loop currents tend to blur or distort the directional effects, so that sharply directional indications or signals are not received. The present invention relates to means for overcoming or neutralizing such undesirable currents in the system which results from an

electrically non-symmetrical or unbalanced relation of an aerial or aerials. To that end, there is inserted in the open aerial a loop placed in inductive relation to the loop of the closed aerial, as will be hereafter more particularly described.

In the accompanying drawing,

Fig. 1 shows diagrammatically one system embodying the invention; and

Fig. 2 shows diagrammatically another system embodying the invention.

Referring to Figure 1, A represents a closed loop or coil aerial of one or more turns, the total horizontal length of the loop being preferably less than a quarter wave length; and this loop A is tuned to the distant station wave length by means of an inductance coil L¹ and a variable condenser C. A conductor B is connected at a point X near the inductance L¹ to the loop or coil A to form therewith an open aerial. The conductor B comprises in series a coil or loop A', interwound or otherwise closely coupled with the loop A so as to be electro-magnetically as well as electro-statically coupled thereto. The other end of conductor or open aerial B is connected to ground or counterpoise G by way of an inductance coil L', an inductance coil L² which is preferably variable for tuning the system as an open antenna circuit, and a variable resistance R. The two loops A and A' are erected in vertical planes, which generally include the great circle bearing of the distant station, i. e., with their planes in line with the direction of wave propagation, as when the static originates 180° from the signal; although in some cases it may be best to erect the two loops A and A' in a vertical plane other than the great circle bearing of the distant station. In any case, the two loops A and A' may be mounted universally in such way as to permit of varying their planes and also varying their coupling with one another, such variable coupling being shown by symbol in Figs. 1 and 2.

A secondary inductance coil S is in inductive relation with the coil L² or the coil L', or, with both of said coils, and is associated in a circuit with any usual detector such as the audion D of well-known construction. The coils L', L² and S are adjustably coupled together as indicated at K and M, whereby currents in the aerials can be varied in their effect on the secondary.

circuit. C' is a variable condenser for tuning the detector circuit, and C^2 , C^3 and C^4 are condensers arranged as well known.

In Figure 1, the loops A and A' are shown diagrammatically as of single turns, although in practice these loops A and A' may consist of a plurality of turns, such as three or more each, like the construction of Figure 2, the several turns of each loop being connected in series and all arranged alongside of each other in close juxtaposition or interwound, i. e., a turn of one loop alternating with a turn of the other as shown in Figure 2.

The combination of an open aerial and a closed loop or coil aerial, when the signal or static currents developed in these aerials are made substantially equal in their effect upon the secondary, results in what is known as unilateral or one-sided reception,—that is to say, the system receives waves most strongly from one particular direction, this being along a horizontal line lying in the vertical plane, including the plane of the loop aerial. From a direction 180° from this or in the opposite direction, the reception is substantially zero, this resulting from the fact that when the waves arrive from the opposite direction, they produce a current in the loop aerial in the reverse direction to that produced in the loop aerial by waves arriving from the direction of maximum reception; whereas the currents in the open aerial do not change direction and are the same regardless of the locus of the transmitting station. Because of this, the two currents,—the loop and the open aerial currents,—add together and produce a strong signal when the waves arrive from the desired station; whereas with waves arriving from the opposite direction, these two currents,—the loop and the open aerial current,—are in opposition and their effect upon the secondary is substantially zero.

The invention differs from all prior combinations of loop and open aerial reception known, in that it employs two loops, one of which is tuned to the wave length of the signals and acts in true loop fashion, and the other of which is not tuned as a loop but constitutes a part of the open antenna circuit and is coupled preferably closely, with the first loop.

It is difficult to advance with any certainty a theory to account for the beneficial action observed from this arrangement, but a theory regarding it is substantially as follows. In circuits arranged as above described, but without the second loop A' , there are generated in the tuned loop A not only the true loop currents, but also other currents caused by the unsymmetrical connection of the conductor B to ground or counterpoise, which other currents are out of phase with the true loop currents and

to some extent interfere with their effect. When the second loop A' is included in the open circuit in accordance with this invention other out-of-phase currents traverse it also, and, because of the inductive relation of loop A' with the first or true loop A , tend to neutralize the out-of-phase currents in the true loop. The coils of each loop should be so wound or connected as to place the two sets of out-of-phase currents in opposition. Furthermore, the loops A and A' , when acting as the open circuit (either by means of the direct connection at X , Fig. 1 or by electrostatic or electro-magnetic coupling as in either Figs. 1 and 2, or by both); are non-inductive as to open antenna currents therein. This theory may or may not be correct, but whatever the reason may be, it is found that the inclusion of this second loop A' in the open circuit as herein described materially aids in the directional effect and interference and static elimination of the system.

In order that currents in the true loop A can be properly added (in their effect upon the secondary or detector circuit) to the currents due to the same waves acting upon the open circuit B , it is desirable that the phases of these currents—the loop and the open—be made the same, the currents in the open antenna being 90° out of phase with the current in the loop A , as explained in U. S. Patent No. 876,996 to Pickard referred to above. In the system illustrated in Fig. 1, the means for bringing into phase both sets of currents in their action on the common receiving apparatus consists of the coupling between coils L' and L^2 and S . When energy in the form of oscillating or alternating currents in the one circuit is transferred to the other by means of such a coupling, in the transfer the phase is changed by 90° , so that in this system the currents flowing in the open circuit $A' B$ (normally 90° out of phase with currents flowing in the loop A) when transferred by way of the coupling between coils L' and L^2 to the loop circuit A are changed in phase by 90° and are so made equal in phase to the currents already existing in the loop circuit A .

In operation, the closed loop circuit A is first tuned, as by variation of condenser C , to the distant station wave length. Then the open circuit $A' B$ is also tuned to the same distant station wave length, as by variation of inductance L^2 . Then coils L' and L^2 are rather closely coupled together, and coil L^2 is rather more loosely coupled to the secondary circuit S . This secondary circuit may have, as indicated in the drawing, one of the forms of oscillating audion detector, and such a secondary circuit would be employed for undamped or continuous wave reception; or a crystal or other form

of detector might be used for reception, particularly when damped or spark signals are to be received. Any of the well-known forms of secondary or detector circuits may be employed in this invention.

A simple closed loop aerial may also develop open antenna current, "antenna effect," which is neither in phase with the true loop current nor in quadrature therewith. This is due to the fact that one part of the loop may not be electrically symmetrical with another part, and its capacity to ground therefore may be different at different points on the loop circuit. These antenna effect currents impair the sharply directional properties of the loop.

In Figure 2 is shown a modified form of the invention, also adapted to eliminate this "antenna effect", in which the closed loop aerial A and open aerial or antenna B are provided, but in which the circuits of the two aerials are independent and distinct as far as being conductively connected together. The loop aerial A has in series therewith an adjustable tuning condenser C and a primary inductance coil L³ and as here shown comprises a loop of three turns. The open aerial or antenna B includes a loop A' of preferably three turns, which are preferably interwound, as shown in Fig. 2, with the turns of the loop A, so that the two loops A and A' are inductively and statically coupled together. The amount of coupling between the loops A and A' may be varied by moving or swinging the loops relatively toward one another. Unlike the arrangement in Fig. 1, however, one end X' of the open aerial B, including the coil A', is free or unconnected to the loop A. The other end of the aerial B is connected to ground or counterpoise E. The open aerial B has in series therewith an adjustable condenser C', an adjustable primary inductance coil L⁴, and a variable resistance R. The inductance coils L³ and L⁴ constitute a variable coupling K, and these coils L³ and L⁴ are in turn coupled to a secondary inductance coil S (variable coupling M) of a secondary or detector circuit such as the one above described and shown in Fig. 1.

Embodiments of the invention shown in Figs. 1 and 2 and installed at the United States naval radio station at Otter Cliffs, Maine, each had a closed tuned loop A of three turns, this loop being 125 feet long and 25 feet high, with ten-inch spacing between the turns. (The only difference between the two embodiments was the interconnection at X in the case of the embodiment of Fig. 1.) The open independent aerial A' B with its loop of three turns of like dimensions with closed loop A was closely coupled with closed loop A in the manner shown in Fig. 2 (and on one occa-

sion was closely coupled by side by side arrangement of the two loops without interwinding) and connected to ground either through an inductance L⁴ (Fig. 2) or through coupling coil L' and variable inductance L² (Fig. 1), the values of these coils depending on the received wave length and the connection to ground being also through variable resistance R which in the use of the invention was varied between a few hundred ohms and seventy-five hundred ohms. Resistance R, however, may be lumped or it may be distributed through a circuit in any well known manner. Although resistance R is preferably variable, yet it may be fixed. Coils L' and L² were generally of twenty-two milli-henrys. Coil L² was generally made variable between the limits of 0 and 80 milli-henrys. Among the secondary circuits S employed was one which included a 40 milli-henry coil shunted by a variable air condenser C" of about .002 mfd. maximum value, while the condenser C in the closed loop circuit A generally had the maximum value .004 mfd.

The interwinding of the loops A and A' (Figs. 1 and 2) functioned to increase and sharpen the uni-directional effects (as evidenced by improvement of signal-static ratio, i. e., reduction of static), due possibly to the neutralization or elimination of the unbalancing currents or open antenna currents or "antenna effect" in the closed loop A as above described.

The resistance R shown in Figures 1 and 2 is believed to prevent the impact excitation of static or other disturbances from setting up complex or coupling waves in the system as a whole. Such complex oscillations result from the successive transfer and re-transfer of energy between coupled circuits of feeble damping and are objectionable because they tend to destroy or impair the directional reception of the system, on which reception the elimination of disturbances is believed to depend. By increasing the damping of either or both of the aerials, which is most readily done by means of the lumped resistance R as shown, such transfer and retransfer of energy is prevented and no coupling waves are formed. The preferred place for the insertion of the resistance R is in the open antenna A' B because, in general, this circuit collects more energy from the static and the signal waves than does the loop A, and the resistance may, therefore, perform two functions—first, the damping of the entire receiving system to prevent complex wave formation, and, second, the reduction of the currents in the open circuit A' B due to static and signal waves, to approximate equality with that of the true loop A. In case the loop A receives more energy from static and signal waves than the open circuit A' B, the

- resistance R may be placed in the triplex loop A and performs the same functions. The resistance R is variable, as above mentioned, and, after the system of Figures 1 or 2 is adjusted or tuned in a manner like that described above in connection with Figure 1, the resistance R can be varied or adjusted until the best static-signal ratio or optimum static reduction is obtained.
10. It appears to be important that the effect upon the secondary circuit S of currents due to static in the open circuit A' , B be made approximately the same as that of currents due to static in the loop circuit A , and to this end the couplings K and M between L' , L^2 and S are made independently variable over wide limits, according to any of the well-known methods of varying the coupling between circuits.
15. In some instances, it is preferred to make the coupling between the loops A and A' variable, this being accomplished by physically varying the separation between them. The effect of this coupling between loops A and A' appears to be in part electro-static, and it may be that the beneficial effects observed from a variation of the coupling or separation between loops A and A' is due in part to a change in electro-static coupling or capacity from one set of turns to the other.
20. The installation at Otter Cliffs was for trans-Atlantic communication at long wave lengths. For shorter wave lengths and range there may be used smaller loops,—that is to say, loops which either have a less number of turns or which have individual turns of smaller enclosed area than those above described. Also the inductances and capacities, such as the coils L' , L^2 or L^4 and S and the condensers C and C' , should be proportioned to the wave length to be received, as is well understood in general practice.
25. With this invention may be used any desired additional means of preventing interference by static or by foreign signals, such for example as the rotary tone condenser of my prior Patent, No. 1,211,963 of January 11, 1917, which I have found to be efficient for this purpose.
30. What is claimed and desired to secure by Letters Patent is:
1. A receiving system for wireless signals comprising a tunable closed loop aerial, a tunable open aerial separate structurally from said loop and having a loop in series therewith and in coupled relation with the first loop, and means for adding the currents in said aerials for operating a detector.
  2. A receiving system for wireless signals comprising a plurality of aerials having different directional properties and structurally separate and having a plurality of couplings between them, one for neutralizing out-of-phase currents and another for adding useful currents in said aerials.
  3. A receiving system for wireless signals comprising a closed loop aerial of multiple turns and an open aerial having a loop of multiple turns interwound with the turns of the closed loop.
  4. A closed loop aerial of multiple turns, an open aerial having a loop of multiple turns interwound with the turns of the closed loop, and a detector circuit coupled to both said aerial systems.
  5. A receiving system for wireless signals comprising a tunable closed loop aerial of multiple turns, a tunable open aerial having a loop of multiple turns interwound with the turns of the first loop forming a coupling between them.
  6. A receiving system for wireless signals comprising a closed loop aerial of multiple turns, an open aerial having a loop of multiple turns interwound and alternating with the turns of the first loop forming a coupling between them, phase-changing means combining the currents of the two loops, and means for detecting said combined currents.
  7. A receiving system for wireless signals comprising a closed loop aerial of multiple turns, an open aerial having a loop of multiple turns interwound and alternating with the turns of the first loop forming a coupling between them, a resistance associated with said aerials, and means for detecting currents set up in said aerials.
  8. A receiving system for wireless signals comprising a closed loop aerial having means for tuning the same, an open aerial structurally separate from said loop and having a loop in series therewith and in coupled relation with the first loop, means for tuning said open aerial, a resistance associated with said aerials, and means for adding the currents in said aerials for operating a detector.
  9. A receiving system for wireless signals comprising a closed loop aerial of multiple turns, a structurally separate open aerial of multiple turns with its turns interwound and alternating with the turns of the closed aerial providing a coupling between them, a resistance associated with said aerials, means for tuning the aerials, a coupling between said aerials for combining useful currents in the aerials, and means for detecting said combined currents.
  10. A receiving system for wireless signals comprising an open aerial having a coil aerial associated therewith, a coil aerial structurally distinct from said first aerials, and means for detecting currents in said aerials.
  11. A receiving system for wireless signals comprising an open aerial having a coil aerial in series therewith, a closed loop aerial structurally distinct from said open aerial.

and means for detecting currents in said aerials.

12. A receiving system for wireless signals comprising an open aerial having a coil aerial therein, a closed loop aerial structurally distinct from said open aerial, coupling means between said aerials and means for detecting currents in said aerials.

13. A receiving system for wireless signals comprising an open aerial having a coil aerial therein, a structurally distinct aerial having different directional properties from said open aerial, coupling means for said aerials and detecting means for said aerials, said aerials being adapted to receive unilaterally.

14. A radio system comprising a closed loop aerial; and an open aerial having a coil in series therewith coupled to said closed loop aerial as a whole, said aerials being conductively separate from each other, and a circuit associated with said aerials.

15. A radio system comprising aerials having loops of multitrans interwound with each other and a circuit associated with said aerials.

16. A radio system comprising an aerial

of the closed functionally ungrounded loop circuit type; and a second aerial of the open functionally grounded circuit type and including a loop arranged substantially as a whole in electrostatic and electromagnetic relation to said closed loop circuit substantially as a whole.

17. A radio system comprising a closed loop aerial and an open aerial having an open coil closely coupled to said loop aerial as a whole, said aerials being conductively distinct, and a circuit associated with said aerials.

18. A radio system comprising an aerial of the closed functionally ungrounded loop circuit type; a second aerial of the open functionally grounded circuit type and including a loop arranged substantially as a whole in electrostatic and electromagnetic relation to said closed loop circuit substantially as a whole; said two loop circuits having also a lumped reactance coupling with one another; and an operating circuit common to both said open and closed loop circuits; all substantially as described.

JOHN A. PROCTOR.
